UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed October 26, 1927. Serial No. 228,774.

This invention relates to means for rotating the platen of a typewriting machine, in a single sweep, to expedite positioning of a work-sheet for certain entries.

In the condensed-billing mechanism usually employed upon the Underwood typewriter, the work-sheets are swept around the platen by means of a long handle, which is connected to drive a wheel which is fixed upon the shaft upon which the platen is also fixed.

A feature of the present invention is provision for effecting minute rotative adjustments of the platen, at will, relatively to the platen-sweep mechanism.

To carry out my invention, the condensed-billing driver may be taken out of its usual position at the right-hand end of the platen, and by suitable means may be directly connected to a clutch-drum at the left-hand end of the platen. The condensed-billing mechanism therefore will remain entirely stationary during the rotative readjustment of the platen while the clutch is released. Therefore there is no disturbance of the operation of the condensed-billing mechanism arising through rotative adjustment of the platen relatively to the condensed-billing drive-wheel; but the operation of the condensed-billing mechanism is perfect at all readjustments of the platen relatively to the drive-wheel.

Preferably the same clutch-drum is connected to both the condensed-billing drive-wheel and the line-space wheel, thereby economizing space, weight and cost, and also adapting the invention to use with parts of the standard Underwood mechanism for clutching the platen to the line-space wheel.

The invention provides an inexpensive and simple platen-sweep device which may be advantageously used for filling in blank spaces on duplicates or circulars in order to obtain uniform spacing and neat looking appearance of the entries in the quickest possible time, said attachment including a hand-operated pawl-and-ratchet device or platen-sweep mechanism to be used on standard machines in combination with a variable line-spacing device or clutch. This clutch mech-

anism permits the platen-sweep-drive-wheel to be disconnected from the platen-shaft so that the platen may be freely rotated to adjust a work-sheet thereon to a certain reference-line, while the drive-wheel is stationary. Thereafter, the clutch may be rendered operative to engage said drive-wheel, and the adjacent platen-sweep may be brought to rotate the platen through a plurality of line-spaces to position the first writing line of the entry proper, which then, after sweep-lever and pawl are automatically disengaged, may be written line by line in the ordinary manner or rotated at will.

The clutch, as indicated in the drawings, includes an outer clutch member or drum rotatably mounted upon the platen-shaft. A drive-wheel, rigidly fastened to said outer clutch-member, may be rendered effective for platen-sweeping work by causing expandable inner clutch-members or grips to engage the inner periphery of the drum, said grips being mounted upon the shaft to rotate therewith. An axially-operating thumb-piece may be in control of a tapered sleeve or cam provided upon the shaft and effective to urge said inner clutch-members into operative engagement with the drum.

According to one feature of the invention, the platen-sweep-mechanism is compactly arranged upon said outer clutch-member, with which it is to co-operate, so as to minimize the space occupied upon the platen-shaft, whereby the driving wheel is placed in rigid relation with the line-space-wheel while the associated pawl-carrying operating lever is loosely mounted for oscillating movement about the platen-axis. The same clutch connects the line-space-wheel to the platen, and the latter wheel may be rigid with the drive-wheel.

Another feature provides means for independently attaching and detaching said operating lever.

A further feature resides in the proximity to each other of the clutch-governing finger-piece and the platen-rotating handle, facilitating their alternate operation, which is required for quick positioning of certain entries.

70

75

85

95

100

In a preferred embodiment of the invention, there are provided upon said clutch-drum peripheral one-way ratchet-teeth to be opposed to those of the line-space-wheel 5 with which they are in rigid relation. A pawl controlled by an oscillating lever may engage said ratchet-teeth to sweep the platen backwardly, which, aside from having operative and constructive advantages, serves the 10 special purpose of conveniently filling in addresses or headings upon duplicated or circular letters, as may be seen in the following description.

Certain features disclosed herein are 15 broadly claimed in my pending application, Serial No. 157,912, filed December 30, 1926, but the claims in this case are limited to features not disclosed in said application.

Other features and advantages will here- 20 inafter appear.

In the accompanying drawings,

Figure 1 is a semi-sectional front elevation to show the combined clutch and platen-sweep mechanism applied to an Underwood machine and assembled upon the left-hand end of the platen-shaft, the right-hand end of the platen being broken away.

Figure 2 is a fragmentary end view of Figure 1, showing the platen-sweep-handle 30 spring-held in ineffective position, and also means to independently attach and detach the operating lever.

Figure 3 is an end view similar to Figure 2, illustrating the manipulation of the operating lever, showing same as being held in extreme operative position.

Figure 4 is a perspective view, showing 40 some of the parts of the platen-sweep mechanism disassembled to illustrate the novel method of assembling them.

In Figure 1, a type-bar 10 is shown in dot and dash, which strikes the front of a revolvable platen 11, whose shaft 12 at its left-hand end is shown to be journaled in an end plate 13 of an Underwood typewriter platen-frame and to terminate in a usual finger-wheel 14. A hub or collar 15 may be secured by means of a set screw 16 upon the platen-shaft at either side adjacent to the platen-ends to locate the same within the platen-frame. Between the end plate 13 of the platen-frame and the finger-wheel 14, there is shown the novel combination of a variable line-spacing mechanism or clutch 45 and a platen-sweep mechanism, both to be concentrically assembled upon the shaft. The clutch includes an exterior drum 17, which is formed with a hub 18, to be rotatably mounted upon the platen-shaft. The hub extends from said drum towards said end plate 13 and carries at its end, and shown to be integral therewith, a line-space-wheel 19 which co-operates with a usual detent-roller 20 supported by an arm 21, which is pivoted 50 at 22 upon the end plate 13 and held under

tension by a usual spring 23 encircling said pivot 22. Inner clutch-members are to connect the drum 17, i. e., the line-space-wheel 19 to the platen-shaft 12 for ordinary line-space-work, which may be performed by operating a well-known platen-return and line-space-lever which brings a dog into engagement with the line-space-wheel, said line-space-lever and dog, indicated in Figure 2, 70 at 24 and 25, respectively. 75

Said inner clutch-members may include a hubbed disk 26 secured upon the shaft 12, as by a pin 27, and carrying expansible gripping members, as indicated at 28. To operate the clutch, there is provided a tapered sleeve or cam-member 29 upon the shaft. An axially-operating thumb-piece 30, located adjacent the outer face of the finger-wheel 14, is connected to said cam-sleeve through rods 31 which are carried and guided in said finger-wheel. The thumb-piece, from its ineffective (dot-and-dash) position, may be pressed inwardly to cause the cam-sleeve to urge the inner clutch-members 28 into gripping engagement with the inner periphery of the drum 17. The clutch may be held in or out of engagement by suitable means, not shown on the drawings but clearly shown in the aforesaid Helmond patent.

At 32 a spacing sleeve laterally locates the outer clutch member or drum, at 33 a plate covers the open end of the clutch-drum, while at 34 an apron or cover-plate encloses the line-space mechanism, and is secured at 35 to the carriage-end plate 13 in a well-known Underwood manner.

The platen-sweep mechanism, associated with the variable line-space mechanism just described, includes a one-way ratchet-wheel 36 shown in the form of a rim having teeth opposed to those of the line-space-wheel 19 and being shrunk or otherwise rigidly fastened upon the drum 17, and a driving pawl 37 carried by a sweep-lever 38. The lever 38, loosely mounted upon the said clutch-hub 18 for a swinging movement and occupying part of the space left between the line-space-wheel 19 and the drum 17, has a handle 38^a and may be operated between stops provided upon the cover-plate 34 (see Figure 2). A rigid stoppin 39 at the rear may determine the ineffective position of the lever, where it is normally held by the tension of a spring 40 fastened between the lever and an extension 40^a which is part of the cover-plate. 110

The movement of the operating lever is limited by a stop-screw 41 which may be inserted in different tapped holes 42 for the purpose of adjustment. The driving pawl is pivotally mounted upon the sweep-lever by means of shouldered screw 43 and is to operate in a plane with the associated ratchet-wheel. The tension of a spring 44 fastened between a tail-extension 45 of said pawl and a pin 46 upon the sweep-lever tends to pull said 125 130

pawl into mesh with the ratchet-wheel. In its Figure 2 position, the pawl is held out of engagement by the stop-pin 39 against spring-tension 44, and it will be seen that, 5 as the operating handle is pulled forward, the pawl 37 will engage a tooth in the ratchet 36 and a further pull of the handle will rotate the platen rearwardly or reversely to a line-space direction.

10 In Figure 3, the sweep-lever is held by the operator's finger against spring-tension 40 in extreme operative position, whereby the pawl becomes locked by the stop-screw 41 to prevent the platen from overrunning its intended rearward position, due to vigorous throw of the operating lever. Upon release, the operating lever and pawl will automatically return to neutral. It should be understood that for proper co-operation of the parts, the 15 extreme position of the operating lever should coincide or time with a full engagement between the detent-roller and the teeth of the line-space-wheel.

A novel method of detachably mounting 20 the sweep-lever requires that the lever or cam 38, made of flat material, be formed with a cut-out 47 to fit over the clutch-hub 18. The cut-out, however, at its open end 48 is narrowed down to the shape of a key-hole 25 so as to embrace more than half of the hub 18. The hub has corresponding straddle mill-cuts 35 49 to pass the ends 48 when assembled to the hub, in the direction of arrow (Figure 4), and then axially shifted into contact with the drum or ratchet-wheel 36 to be properly seated upon said hub. A clamp 50 may be assembled to cover the mill-cuts and be locked in place around the hub by screw 51, the clamp also serving as a spacer between the 40 lever and line-space wheel 19.

It will be noted that the line-space wheel 19 with its hub 18 and annular flange 17, that houses the expandible dogs 28, are similar to Helmond, aforesaid, which has become a 45 standard Underwood product; that to this standard part a second ratchet-wheel 36 is added to the flange 17 and a straddle mill slotting cut 49 through the hub is provided for; that within these slots of the hub 18 the operating handle 38^a is assembled to find a 50 rotary bearing upon the hub and held in position by a spacing member 50; that the operating handle 38^a is an assembled unit including a spring-controlled pawl 37 to engage the 55 teeth of the ratchet-wheel 36; and that stops are assembled upon the face of the carriage-end plate 34 to adjustably limit the sweep of the handle in two directions, the restoring movement thereof being effected by the recoil 60 of a spring.

It will also be noted that the reconstructed part 17—36 may replace the original Helmond part 17—19 as a standard part to be employed with all variable line-space assemblies, and which new part provides for a fac-

tory assembly of the platen-sweep or for the subsequent assembly of the platen-sweep by unskilled hands wherever the machine may be located in the field; that the new part 17—19—36 includes a pair of adjoining one-way ratchet-wheels for driving the platen in alternate directions when secured to the platen-shaft by the clutching mechanism; that each ratchet-wheel has an independently operating lever and each lever rotates both ratchet-wheels in unison regardless of the platen-rotating direction; hence the accurate timing of the two wheels cannot be disarranged by the separation of the platen from the platen-shaft in adjusting the printed form of a circular to the typing position for the first typing line; and that the two ratchet-wheels may be integral as shown but spaced apart by a hub to provide for the compact assembly of the handle 38^a between the two wheels.

The operation of typing addresses upon the blank heading of stock form circular letters 52, as illustrated in Figure 1, is as follows: The thumb-piece 30 is pulled outwardly to the dotted position of Figure 1, which releases the platen-shaft from the detented line-space wheel 19 and the platen may be rotated without resistance, except from the feed-rolls 54. A sheet is inserted at the rear of the platen and fed under and around the platen by the use of the finger-wheels 14 until the printed "Dear Sir:" is aligned to the wing-scales 53, as shown. The thumb-piece 30 is now restored to the full-line position of Figure 1, which reclutches the line-space wheel with the platen-shaft, and with the same hand the adjoining handle 38^a is pulled forward, which causes the pawl 37 to engage an adjacent tooth of the ratchet-wheel 36 to rotate the platen in a clockwise direction and back-feed the adjusted circular until the forward sweep of the lever 38 is arrested by the stop 41, whereupon the lever is released by the finger to respond to the tension of the spring 40 to rotate both the lever and pawl 37 to their normal positions of rest against the pin 39. The name is typed and then the usual line-space mechanism provides for the forward line-spacing of the sheet for the subsequent lines of the address, when the circular is removed.

With this combined manipulation of two distinct platen-spacing mechanisms, one mechanism sweeping the platen rearwardly and the other mechanism line-spacing the platen forwardly, the sheet may be quickly aligned to the initial printed line, and quickly reversed for the line typing of the address, which is properly spaced upon the blank heading by mechanical means, and parallelism between the typed lines and the printed lines of the form is preserved, which all tends to give an appearance to the type-addressed

form of a circular which is not readily distinguishable from a fully typewritten letter.

Variations may be resorted to within the scope of the invention, and portions of the improvements may be used without others.

Having thus described my invention, I claim:

1. In a typewriting machine having a platen, a platen-shaft rotatable by a finger-wheel, a line-space wheel, and a clutch mounted upon said shaft for disconnecting at will said line-space wheel from said shaft to independently position a work-sheet with the finger-wheel, a pawl-and-ratchet device to sweep the platen for certain entries upon said work-sheet, said device including a ratchet-wheel which is integral with the line-space wheel, and a pawl-carrying sweep-arm arranged loosely upon the platen-shaft to swing between limits and reversely rotate the reclutched platen through a plurality of line-spaces.
2. In a typewriting machine having a platen; a platen-shaft rotatable by a finger-wheel, a line-space wheel, and a clutch mounted upon said shaft for disconnecting at will said line-space wheel from said shaft to independently position a work-sheet with a finger-wheel, a device to sweep the platen for certain entries upon the positioned work-sheet, said device including a ratchet-wheel which is integral with the line-space wheel, a pawl-carrying arm arranged loosely upon the platen-shaft to swing between limits and reversely rotate the reclutched platen through a plurality of line-spaces, and means to automatically engage and disengage the pawl through the swinging of the operating arm.
3. In a typewriting machine having a platen, a platen-shaft rotatable by a finger-wheel, and a line-space mechanism including a line-space wheel and detent, the combination with a clutch mounted upon said shaft for connecting or disconnecting at will said line-space wheel from said shaft to primarily position a work-sheet independently of the line-space mechanism, said clutch including an exterior drum-like member rotatable upon the shaft and carrying rigidly thereon said line-space wheel and including interior gripping members mounted to rotate with the platen-shaft and operable thereon to engage the drum-member for line-space work, of a device to sweep the platen through a plurality of line-spaces for certain entries upon said work-sheet, said device including a ratchet-wheel rigidly provided upon said drum-member and concentrically thereto, a pawl-carrying operating lever loosely mounted upon said drum-member for oscillating movement about the platen-axis and operable through the pawl to engage said ratchet-wheel for platen-sweep within certain limits when the clutch is operative, and means to automatically restore the lever and pawl to neutral.
4. In a typewriting machine having a platen,

en, a platen-shaft rotatable by a finger-wheel, and a line-space-wheel, a combined clutch and platen-sweep mechanism, said clutch operable for connecting or disconnecting, at will, said line-space-wheel from said shaft to primarily position a work-sheet independently of the line-space-wheel, said clutch including an exterior drum-like member which, by means of a hub, is rotatably mounted upon the platen-shaft and secured against lateral displacement and which at its free end carries rigidly provided thereon said line-space-wheel, and interior gripping members mounted to rotate with the platen-shaft and operable thereon to engage the drum-member for line-space-work, said platen-sweep mechanism as a whole mounted upon the exterior clutch-member and including a ratchet-wheel rigidly fast upon the opposite end of said hub, a pawl-carrying operating lever loosely mounted upon said hub between said line-space-wheel and said ratchet-wheel and operable for oscillating movement between certain limits to sweep the platen through a plurality of line-space distances for certain entries when the clutch is operative and the pawl is engaged with the ratchet-wheel, means to independently attach and detach said operating lever, and means to automatically control the pawl when said pawl-carrying lever is operated.

5. In a typewriting machine having a platen, a platen-shaft rotatable by a finger-wheel, and a line-space-wheel, a combined clutch and platen-sweep mechanism, said clutch operable for connecting or disconnecting, at will, said line-space-wheel from said shaft to independently position a work-sheet, said clutch including an exterior drum-like member which, by means of a hub, is rotatably mounted upon the platen-shaft and secured against lateral displacement thereon and which at its free end carries rigidly fastened thereto said line-space-wheel, and including interior gripping members rotating with the shaft and operable to engage said exterior member for line-space-work, said platen-sweep mechanism, as a whole, mounted upon said exterior clutch-member and including a ratchet-wheel rigidly fast upon the opposite end of said hub, a pawl-carrying operating lever to sweep the platen, at will, for certain entries when the clutch is operative, said lever of flat material to be detachably mounted for oscillating movement upon said hub between said line-space-wheel and said ratchet-wheel, and having at the inner end a cut-out in the shape of a key-hole open at its narrow end to allow the lever to be sidewardly applied to said hub by sliding the narrow end of said cut-out over a correspondingly flattened part of said hub previous to laterally shifting the lever upon the hub, to provide proper bearing of the circular part of the key-hole upon the circular part of the hub,

and means to locate the lever upon said hub for cooperation of the pawl and said ratchet-wheel.

6. In a typewriting machine having a platen, a platen-shaft rotatable by a finger-wheel, and a line-space-wheel, a combined clutch and platen-sweep mechanism, said clutch operable for connecting or disconnecting, at will, said line-space-wheel from said shaft to independently position a work-sheet, said clutch including an exterior drum-like member and interior gripping members rotating with the platen, said exterior member, by means of a hub, rotatably mounted upon the platen-shaft and secured against lateral displacement, and having at its free end rigidly provided said line-space-wheel, said platen-sweep mechanism including a ratchet-wheel rigidly fast upon the opposite end of said hub, and a pawl-carrying operating lever to sweep the platen, at will, for certain entries when the clutch is operative, said lever of flat material to be detachably mounted upon said hub between said line-space-wheel and said ratchet-wheel for oscillating movement and having at its inner end a cut-out in the shape of a key-hole open at its narrow end to allow the lever to be sidewardly applied to said hub by sliding the narrow end of the cut-out over a correspondingly flattened part of said hub previous to axially shifting the lever thereon, to provide proper bearing of the circular part of the key-hole upon the circular part of the hub, and a clamp-member to cover up said flattened part and to locate the lever upon said hub for proper co-operation of the pawl and said ratchet-wheel.

7. In a typewriting machine having a platen, a platen-shaft rotatable by a finger-wheel, and a line-space-wheel, a combined clutch and platen-sweep mechanism, said clutch operable for connecting or disconnecting, at will, said line-space-wheel from said shaft to independently position a work-sheet, said clutch including an exterior drum-like member and interior gripping members, the latter rotating with the platen, said exterior member, by means of a hub, rotatably mounted upon a platen-shaft and secured against lateral displacement, and having at its free end rigidly provided said line-space-wheel, said platen-sweep mechanism, as a whole, mounted upon said exterior clutch-member and including a ratchet-wheel rigidly fast upon the opposite end of said hub, and an operating lever engageable at will with said ratchet-wheel to sweep the platen for certain entries when the clutch is operative, said lever made of flat material to be detachably mounted upon said hub between said line-space-wheel and said ratchet-wheel for oscillating movement upon said hub, the mounting being such that a cut-out at the inner end of said operating lever fits over a flattened part of said hub to primarily position the lever

thereon, and such that an additional axial movement will bring an extreme circular part of said cut-out to properly bear upon a cylindrical part of the hub, and means to hold the lever in place adjacent the ratchet-wheel for proper co-operation therewith. 70

8. In a typewriting machine having a platen, a platen-shaft journaled in the side plates of a platen-frame and rotatable by a finger-wheel, and a line-space-wheel, a combined clutch and platen-sweep mechanism assembled upon said shaft between one of the side plates and the finger-wheel, said clutch operable for connecting or disconnecting, at will, said line-space-wheel from said shaft to primarily position a work-sheet independently of the line-space-wheel, said clutch including an exterior drum-like member and interior gripping members, the latter rotating with the platen, said exterior member, by means of a hub, rotatably mounted upon the platen-shaft and secured against lateral displacement, said hub extending towards the platen and at its free end carrying integral therewith said line-space-wheel, said platen-sweep mechanism including one-way ratchet-teeth formed upon a rim which is secured upon the drum, and a pawl-carrying operating lever to co-operate with said ratchet-teeth to sweep the platen, at will, through a plurality of line-spaces for certain entries when the clutch is operative, said lever to be detachably mounted upon said hub between said line-space-wheel and said ratchet-teeth. 90 95 100

9. In a typewriting machine having a platen, a platen-shaft journaled in side plates of a platen-frame and rotatable by a finger-wheel, and a line-space-wheel, a combined clutch and platen-sweep mechanism conveniently arranged for alternate operation of clutch and platen-sweep to facilitate certain entries, said clutch including a drum-member rotatably mounted upon said platen-shaft and laterally located between one of the side plates of the platen-frame and said finger-wheel and carrying rigidly at its inner end said line-space-wheel, interior clutch-members connected to said shaft and operable to engage said drum-member to connect or disconnect the line-space-wheel from the platen-shaft to independently position a work-sheet, a finger-piece adjacent the outer surface of said finger-wheel and axially movable to operate the clutch, said platen-sweep mechanism including a ratchet-wheel rigidly provided upon said drum-member, a pawl-carrying operating lever loosely mounted upon said drum-member, said ratchet-wheel having teeth opposed to those of the line-space-wheel, so that the operating lever is ineffective when swung to the rear, and may be swung forwardly by the operator's finger to position the platen for a certain entry after said finger-piece is 115 120 125 130

pressed inwardly by the operator's palm to connect the line-space-wheel to the platen, means to automatically control the pawl when the lever is operated, and means to automatically restore the pawl and operating lever to neutral.

10. A circular-addressing mechanism in a typewriting machine having a platen mounted upon a shaft, including a platen-clutch mechanism releasable to free the platen for a finger-wheel rotation thereof, to feed a circular from the rear around under the platen and above the typing line, and then restore the platen to the control of the clutch, a back platen-sweep mechanism including a ratchet-wheel clutched to the shaft by said clutch-mechanism and rotated by a sweep-lever on the platen-shaft, to sweep the platen reversely and back-feed the circular to a typing position predetermined by a stop engaging said lever, and a line-space wheel fixed to the ratchet-wheel and having a line-space lever to line-space the platen and line-feed the circular in typing an address.

11. In a circular-addressing mechanism for a typewriting machine having a platen mounted to be driven by a platen-shaft, a platen-driving member loose on the shaft, a manually-controlled clutch-mechanism connecting said member with said shaft, said member including a pair of spaced-apart parallel annular flanges, each flange having one-way ratchet-teeth of opposite directions,

35 operating levers individual to each toothed flange and means operated by said levers to rotate the platen in reverse directions, one lever swingable about the platen-shaft and compactly disposed between the two flanges.

40 12. In a circular-addressing mechanism for a typewriting machine, the combination with a carriage having a shaft rotatable with a platen, a line-space wheel loose upon the shaft, a clutch-mechanism operable to 45 connect the line-space wheel with the shaft and a line-space lever on the carriage to engage said wheel to rotate the platen by said clutch-mechanism in a line-space direction, of means for sweeping the platen through 50 a distance greater than a line-space, said means including a ratchet-wheel integral with the line-space wheel, and an operating handle swingable upon the shaft and operative to engage said ratchet-wheel and sweep 55 the platen rearwardly by a forward stroke of said operating handle to position the circular prior to a subsequent line-space operation.

60 13. In a circular-addressing mechanism for a typewriting machine having a platen mounted upon a shaft, including a platen-clutch mechanism releasable to free the platen for a finger-wheel rotation thereof, to feed a non-addressed circular from the 65 rear, around under the platen and above the

typing line and then restore the platen to the control of the clutch, a back platen-sweep mechanism including a one-way ratchet-toothed wheel connectible to the shaft by the clutch-mechanism and rotated by a sweep-lever mounted upon the platen-shaft to sweep the platen reversely and back-feed the hand-fed-in circular to an address-typing position predetermined by a stop limiting the platen-backing sweep of said lever, and a one-way ratchet-toothed line-space wheel integral with the back-feeding ratchet-wheel and engageable with a line-space lever to line-space the platen forwardly to line-feed the circular in typing the address.
